United States Patent Office:

WILLIAM DE CAMP, OF NEWARK, NEW JERSEY, ASSIGNOR TO HIMSELF
AND A. R. E. FALCK, OF SAME PLACE.

Letters Patent No. 78,363, dated May 26, 1868.

IMPROVED PARING-KNIFE FOR BOOTS AND SHOES.

The Schedule referred to in these Letters Patent and making part of the same.

TO ALL WHOM IT MAY CONCERN:

Be it known that I, WILLIAM DE CAMP, of the city of Newark, in the county of Essex, and State of New Jersey, have invented certain Improvements in Paring-Knives for Trimming the Soles of Boots and Shoes; and I do declare the following to be a full and exact description of the same, reference being had herein to the drawings that accompany this specification as part of the same.

The nature of my improvement consists in a peculiar guide and guard, adjustable to any thickness of sole, for a paring-knife, and which insures an avoidance of cutting the upper leather of the boot or shoe. In the drawings—

Figure 1 is the complete tool.

Figure 2 denotes the adjusting-wedge to guide the depth of the cut by the knife.

Figure 3 shows the adjustable guard to accommodate varied thickness of soles.

The same letters refer to the same part in each figure.

A handle, A, of wood or other suitable material, is made with an end of the required length, having a groove, Z, therein.

A thin metallic piece, y, is attached to the extreme end of the slot or grooved handle, against which the point of the knife B impinges, being held thereto by the spiral spring W on the shank of the knife, the knife being removed, when necessary, by unhooking the cap-piece D. The edge of the piece y when in use is inserted between the sole and the upper leather in the joint, and, when pressed to the bottom, guides and regulates the cutting by the knife. The piece y being between the point of the knife and the upper, there is no danger of cutting the upper leather.

The knife B passes through, fitting in the adjustable guide-piece V. This piece is moved to and fro to accommodate it to varied thickness of soles by means of the screw S and the thumb-nut r on the end of the handle A, a thread being cut for the screw through the shank of the piece V at n, fig. 3.

To lower or heighten the point of the knife, a wedge, C, is movable under the shoulders of V, the wedge being held in place by the thumb-nut p, and the adjustable guide by the thumb-nut q.

The screw S passes loosely through the shank of the wedge C, at o.

What I claim, and desire to secure, is—

The handle A, guide-piece y, adjuster V, wedge C, knife B, and the screw S, all combined, constructed, and arranged substantially in the manner and for the purpose specified and shown.

WILLIAM DE CAMP.

Witnesses:
